TRACTION ELEMENT FOR FORMED CONTAINERS

Robert J. McCormick and Robert J. Turnen, Findlay, and Willard J. Rathbun, Haskins, Ohio, assignors to The Dow Chemical Company, Midland, Mich., a corporation of Delaware

Filed Feb. 5, 1964, Ser. No. 342,665

4 Claims. (Cl. 229—5.5)

This invention relates generally to improvements in formed containers, and, more particularly, to a traction element formed in the bottom of containers for improved handling thereof during filling and capping operations.

While in the past, legs or other projections on the bottom of containers have been known, they have been included for such purposes as providing better insulation from heating or allowing the container to stand upright. In some paper containers, a bottom projection, forming a false bottom, has been present merely because this is the result of the way the bottom wall of the container is fixed in place. None of these projections have been found to appreciably provide improved handling during filling and capping operations.

When a purpose such as that discussed above is not present, it has been customary to form the containers, particularly those made of plastic, with a generally flat bottom. It is customary to transport these containers with their bottoms on moving wire belts, such as used on the Anderson 34F or Anderson 34O filling machines, products of Anderson Bros. Manufacturing Co. of Rockford, Illinois. Such flat bottomed containers have not been completely satisfactory for when they are used with the aforementioned machines there has been a very decided tendency for them to slip on the wire belts. Thus, the speed at which prior containers could be moved from one station to another with automatic filling and capping equipment has been relatively limited in the past.

Accordingly, it is an object of the present invention to provide improved container structures which can speed up filling and capping operations on automatic equipment.

Another object of the present invention is to provide a modification in the bottom structure of plastic containers and the like to give them greater traction when carried on moving wire belts.

Still another object of the present invention is to provide a uniquely constructed container including a novel traction ring on the bottom thereof to decrease the conveying time necessary for filling and capping.

Briefly then, the present invention relates to the provision of a downwardly projecting relatively thin ring extending from the container bottom wall, which ring has a cross section defining an inverted truncated triangle to provide better traction for the container when it is being conveyed along an automatic filling and capping belt line.

Yet additional objects and advantages of the present invention, and its numerous cognate benefits and features are even more apparent and manifest in and by the ensuing description and specification taken in conjunction with the accompanying drawing in which, wheresoever possible, like characters of reference designate corresponding material and parts throughout the several views thereof, in which:

FIGURE 1 is an elevational view of apparatus for filling and capping cup-like containers;

FIGURE 2 is an enlarged fragmentary plan view thereof as seen from reference line 2—2 of FIGURE 1;

FIGURE 3 is a side elevational view of a lower portion of a container showing a traction ring constructed according to the principles of the present invention;

FIGURE 4 is a bottom view thereof;

FIGURE 5 is an enlarged fragmentary cross-sectional view thereof taken along reference line 3—3 of FIGURE 2, with the traction ring engaged with a wire belt; and

FIGURE 6 is a view similar to FIGURE 5 only with the traction ring disengaged with a wire belt.

Cup-like containers 10, described in more detail hereinafter, are generally filled and capped by way of a progressively continuous operation such as that typically illustrated by apparatus 12 of FIGURES 1 and 2. Here containers 10 are dropped from a dispenser 14 onto an endless wire belt-type conveyor 16. Each container is then progressively moved under a hopper 18 for filling and thence under a capper 20 for placement of a lid 12 cover on the container. Thence, each container travels down an inclined coding conveyor 22 and a slide 24 onto a collection table 26.

Stop pins 28 are employed to prevent the containers from moving forward with conveyor 16 until the preceding container is filled or capped, as the case may be. This is more clearly shown in FIGURE 2 wherein a pair of pins 28 are in a raised position preventing a container from being carried by conveyor 16 in the direction indicated by the arrow. When it is desired to again permit container 10 to be employed, stop pins are lowered below the bottommost extent of the container. In the drawing, conveyor 16 is shown formed of a plurality of wire bands 30 between which the stop pins 28 are located.

Each container 10, thermoformed from a plastic material such as polystyrene for example, includes a side wall 32 from which extends a downwardly projecting inwardly disposed relatively thin ring, traction element or ridge 34 which, in effect, provides the container 10 with recessed portions 36 and 38 in the bottom wall thereof. In container 10, ring 34 is formed with an inclined outer wall 40 and a vertical inner wall 42 to form an inverted truncated right triangular cross section, as best seen in FIGURES 5 and 6. Truncate base 44 of projecting ring 34, circumferentially continuous in this particular embodiment, thus form the bottommost extent of the container rather than portion 36, which would otherwise have been the bottommost extent if ring 34 were not included.

Each wire band 30 is in the form of a wire spiral, as most obvious when viewed in FIGURES 5 and 6, and, as viewed in elevation, appears to be a plurality of W's connected together. Certain legs 46 of the W's are inclined upwardly away from the direction of travel of band 30, as indicated by the arrow, while other legs 48 of the W's are inclined upwardly toward the direction of travel of band 30. Adjacent legs 46 and 48 appear to be connected by upper and lower apex sections 50 and 52, respectively.

It can thus be readily seen that inclined wall 40 is engaged by apex section 50 and generally by a portion of leg 46 of band 30 when located thereagainst and between coils since base 44 is of a width less than the space between adjacent apex sections 50 of band 30. While both wall 40 and leg 46 are sloped generally alike, it is preferably that the slope of wall 40 be somewhat greater, from the vertical, than that of leg 46. However, wall 40 still must have enough inclination from the horizontal to permit base 44 to seat between adjacent apex sections 50. An inclination which has worked well for wall 40 has been about forty-five degrees from the vertical. An inclination of twenty degrees from the vertical is common for leg 46.

It is preferable that wall 42 be substantially vertical such that it is firmly prevented from sliding forward on belts 30 by apex sections 50. Traction ring 34 will readily slide by band 30, as seen in FIGURE 6, when the container is engaged by stop pins 28. Ring 34 thus provides for better traction when the container is carried from

station to station during the usual automatic filling and capping operations with a resultant increase in the capacity of the equipment. Also, because of the reduced bottom surface contact area provided by ring 34, containers 10 will slip more readily down flat surfaces such as that found in slide 24.

While certain representative embodiments and details have been shown for the purpose of illustrating the invention, it will be apparent to those skilled in the art that various changes and modifications can be made therein without departing from the spirit and scope of the invention.

Accordingly, what is claimed as new is:

1. A container adapted to be conveyed for filling and capping on a conveyor comprising a plurality of endless bands each formed of spiralled adjacent coils of wire with the legs of said coils being inclined with respect to the vertical, said container having a side wall and a bottom wall, a traction element integral with said bottom wall and having a cross-sectional configuration of a truncated substantially right triangle, the truncate base of said triangle forming the bottommost extent of said container, said base having a width less than the space between adjacent coils of said bands, the outer wall of said element forming one leg of said triangle and being inclined upwardly from said base towards said side wall at

5 an angle intermediate the horizontal and vertical but greater than the inclination of the legs of said coils, the inner wall of said element forming the substantially vertical leg of said triangle, whereby said container will be readily movable by said bands when said element is engaged between adjacent coils thereof but will permit said band readily to slip by said element when said container is purposely stopped by other means while on said moving bands.

10 2. The container of claim 1 wherein the angular inclination of said outer wall is greater than 20 degrees.

3. The container of claim 2, wherein the angular inclination of said outer wall is about 45 degrees.

15 4. The container of claim 3 wherein said element is in the form of a continuous ring adjacent the periphery of said bottom wall.
